PHONOGRAPH RECORD RESURFACING
MACHINE

Charles Huenlich, Bloomfield, N. J., assignor to
Thomas A. Edison, Incorporated, West Orange,
N. J., a corporation of New Jersey

Application January 19, 1939, Serial No. 251,658

16 Claims. (Cl. 82—1.1)

This invention relates to phonograph record resurfacing machines, and more particularly to improvements in machines of the type employed for shaving or resurfacing wax-like or other records, such as are commonly used in connection with commercial phonographs or dictating machines.

Record resurfacing machines of the type above mentioned commonly comprise a mandrel for supporting a record for rotation, an end-gate for the mandrel normally latched in a closed or supporting position, a resurfacing tool mounted on a carriage which is moved across the record by a feeding means driven coordinately with the rotation of the mandrel, and control means for starting and stopping the operation of the machine. The resurfacing tool is movable into operative position relative to the record to cause, as the record is rotated and the tool is moved steadily thereacross, a resurfacing, or a cutting away of a surface layer, of the record for the purpose of removing recordations therefrom to permit a re-use of the record.

In the usual operation of a record resurfacing machine the end-gate is first opened to permit a record to be mounted on the mandrel. When the record is mounted the end-gate is closed, the tool is set in operative position and the carriage is moved into an initial or start position, after which the machine is set in operation to cause a surface layer of the record to be cut away. The machine is then stopped, the end-gate is opened, and the record is ejected from the machine as by a suitable record ejecting means.

It is an object of my invention to provide simple means for facilitating the operation of record resurfacing machines of the type above described.

It is another object of my invention to eject a record from the resurfacing machine by performing but a single manipulation on the machine. A feature of my invention is to provide such means as will cause the record to be ejected and the end-gate to be opened coincidentally with the unlatching of the latter from its closed or supporting position.

Another object of my invention is to insure the stopping of the machine when the end-gate is moved into an open or non-supporting position; in accordance with my invention, this is done by the provision of means for automatically stopping the machine when the end-gate is unlatched.

Another object of my invention is to release

the resurfacing tool from set position upon the unlatching of the end-gate.

Another object of my invention is to provide means to insure that the machine will be in a stopped condition whenever the resurfacing tool is set into operative position.

A further object of my invention is to automatically stop the machine as an incident of releasing the tool from a set or operative position.

A still further object of my invention is to stop the machine, release the resurfacing tool from operative position and eject a record from the machine as an incident of unlatching the end-gate from its closed or supporting position.

Other objects and features of my invention will more fully appear from the following description and the appended claims.

In the description of my invention reference is had to the accompanying drawings, of which:

Figure 1 is a top plan view of a phonograph record resurfacing machine in which my invention is incorporated;

Fig. 2 is a vertical right-hand view of the mechanism of Fig. 1, the base plate of the machine and parts thereabove appearing in cross section as along the line 2—2 of that figure;

Fig. 3 is a fragmentary plan view of the mechanism of Fig. 1, principally showing the inter-linkage means between the machine-controlling means (the main switch appearing in "on" position), and the end-gate latching means, the record ejector and the tool-setting means;

Fig. 4 is a plan view of a portion of the mechanism of Fig. 3 showing the relative positions between parts of the mechanism when the main switch is in "off" position; and

Fig. 5 is a diagrammatic view of the electrical circuit of the machine of Fig. 1.

Reference being had to Figs. 1 and 2 there will be seen a phonograph record resurfacing machine comprising a base plate 1 having a left-hand upright standard 2, right-hand upright standards 3 and 4 and an intermediate upright standard 5. In the right-hand portion of the base plate 1 there is also provided an upright boss 6 on which there is pivotally mounted by a screw 7 an end-gate 8. This end-gate is biased into open or non-supporting position by a torsional spring 8', well known in the art; the end-gate is, however, normally held in a closed or supporting position shown in Fig. 1 by a latch 9. This latch is pivoted to the right end portion 10 of a guide rail 11 which extends laterally along the forward part of the machine. The end-gate 8 supports a conically pointed stud 12.

adjustable with respect thereto by an adjusting screw 13; the left-hand standard 2 supports another conically pointed stud 14 secured thereto by a set screw 15. The studs 14 and 12 form 5 left and right thrust bearings for a shaft 16 which passes through an oversized hole 17 in the intermediate standard 5 and which carries a mandrel 18 for holding a cylindrical record 19 to be resurfaced. In the operation of mounting 10 a record on the mandrel 18, or removing a record therefrom, the end-gate 8 is opened to expose the right or open end of the mandrel. Such opening of the end-gate will occur whenever the latch 9 is moved to an unlatching position, by reason 15 of the end-gate being biased into open position by the torsional spring 8'. When the end-gate is open the shaft 16 is intermediately supported by the standard 5 and retained in engagement with the stud 14 by means of a collar 20, secured 20 to the shaft by a screw 21, which abuts against the intermediate standard 5 to limit movement of the shaft in a rightward direction.

When the end-gate 8 is closed the mandrel 18 is rotatably supported in parallel relation to the 25 guide rail 11. Also in parallel relation to the guide rail 11 is a laterally extending rod 21 supported by the left and right standards 2 and 3. Slidably and tiltably mounted on the rod 21 is a carriage 22 having a sleeve bearing 22' embracing 30 the rod. As shown in Fig. 2, the carriage 22 has a relatively heavy arm 23 curved forwardly over the mandrel 18 and terminating in a shoe 23' which normally slidably rests on the guide rail 11. In the use of the machine the carriage 22 is 35 fed or moved steadily in a leftward direction across the mandrel 18 coincidentally with a rotation of the latter. The carriage-feeding means comprises a laterally extending feed screw 24 rotatably supported by the left and right 40 standards 2 and 4 and having a pulley 25 adapted to be coupled by a belt (not shown) to a drive pulley 26 on the shaft 16. Secured to the carriage sleeve 22' by the screws 27 is a resilient and rearwardly extending arm 28 carrying a feed-nut 29 45 which normally engages the underside of the feed-screw 24. The feed nut may be moved downwardly out of engagement with the feed-screw 24 by tilting the carriage arm 23 upwardly. When the carriage arm 23 is tilted upwardly the 50 carriage is free to be manually moved across the mandrel 18. To limit the upward tilting of the carriage arm 23 there is provided on the carriage a downwardly extending arm 30 which is adapted to contact a stop or ridge 31 on the 55 base plate 1.

On the right side of the carriage there is a boss 32 which substantially overlies the rod 21. This boss carries a resurfacing tool 33 comprising a knife blade 34 mounted on a knife bar 35 60 which is slidably supported by the boss 32 for movement towards and away from the record 19. The means for setting the resurfacing tool into operative position—a position of the tool in which the knife blade 34 engages the record—and for 65 releasing the same may be of a well known construction such as is disclosed in Brown Patent No. 2,137,383, issued November 22, 1938 and entitled "Record shaving machine."

Such tool-setting and tool-releasing means 70 may, in the present instance, be sufficiently described by the following statements: A cap 36 is slidably mounted on the boss 32, is guided by a guide rod 37, and is resiliently coupled to the knife bar 35 by a compression spring 38, coiled about 75 the knife bar between a shoulder 35' on the bar

and the top of the cap 36, so that when the cap is moved downwardly towards the record the knife bar 35 is yieldably moved therewith. The cap 36 is urged upwardly by a compression spring 39, but upward movement of the cap 36 relative to the bar 35 is limited by a head 40 on the knife bar. By reason of the upward biasing of the cap 36 the knife bar 35 is normally maintained in inoperative position, this position being defined by the contact of a collar 41 on the bar 35 with the underside 41' of the boss 32. The setting and release of the tool 33 is controlled by a lever 42 pivoted on the right side of the boss 32 and having a short arm 43 which is coupled to the cap 36 by an angular link 44, the link being pivoted to the arm 43 by a pin 45 and to the cap 36 by a pivot screw 46 which slidably passes through a slot 44' in the link.

As the lever 42 is swung forwardly in a counter-clockwise direction into its set position, shown in Fig. 2, the cap 36 and the knife bar 35 are moved towards the record to cause the tool to be set in operative position. Such tool-setting movement of the lever 42 is limited to the position shown in Fig. 2 by the impingement of the link 44 against a hub 42' of the lever. When the lever 42 is in this set position, the pin 45 is slightly past dead center with respect to the pivot axes of the lever 42 and the pivot screw 46, and, by reason of the upward biasing of the cap 36, the lever 42 is then urged in a counter-clockwise direction, the lever being thus releasably held in its set position and the tool 33 being yieldably maintained in operative position. However a slight "tripping" movement of the lever 42 in a clockwise direction such as to return the pin 45 across the dead-center line aforementioned will cause, by reason of the upward biasing of the cap 36, the tool to be released from operative position.

In the operation of the machine the carriage is first manually moved to bring the tool into a position overlying the record and the tool is set into operative position. The carriage is then moved into start position—the position of the 45 carriage when the tool is to the right of the record—and the machine is put into operation to cause the record to be rotated and the carriage to be fed in a leftward direction across the record. Such rotation of the record and feeding of the 50 carriage may be effected by a suitable electrical motor M, schematically shown in Fig. 5, which may be located beneath the base plate 1 and be coupled to a pulley 47 on the shaft 16 as by a belt (not shown) which may pass through an 55 opening 48 in the base plate. As the tool 33 traverses the record in the operation of the machine a surface layer of the record is cut away, this cut-away layer being carried by a chip chute 49 downwardly through an opening 50 in the 60 base plate. When the carriage has reached its terminal position, the tool 33 then having traversed the record, the machine may be stopped so that the operator may inspect the record to determine if another cut from the record is necessary. Such stopping of the machine may, if desired, be automatically effected by an "on" and "off" limit switch 51 secured by the screws 52 to the top side of the base plate 1 in the rearward lefthand portion thereof. The switch 51 70 may be serially connected, as by a cable 53, in a power supply circuit 54 (see Fig. 5) adapted for connecting the motor M with a suitable source of power by way of a plug 55. The switch is biased into "on" position and is provided with a 75

push button 56 movable leftwardly, as shown in Fig. 1, to throw the switch into "off" position. Extending rearwardly of the carriage 22 is a lug 57 carrying an adjustable screw 58 adapted to contact the button 56 and to thereby throw the switch 51 into "off" position, as the carriage 22 is moved into its terminal position.

The control means of the machine also comprises a switch 59, hereinafter referred to as the main switch, which is secured by a bracket 60 to the underside of the base plate 1 in the forward right-hand portion thereof. The switch 59 is preferably of the toggle variety adapted to snap into its "on" and "off" positions, and is serially connected, as by the terminals 61, into the power supply circuit 54. The switch 59 is manually operable into its "on" and "off" positions by means of a forwardly extending control lever 62 having a shaft 62' extending downwardly through a boss 63 provided on the underside of the base plate 1. Beneath the base plate 1 there is provided a small plate 64 which is secured to the shaft 62' by means of a collar 65 welded to the plate and connected by a pin 66 to the shaft 62'. The plate 64 has a rearwardly extending arm 67 carrying a slotted, pivoted stud 68 through which slidably passes an operating arm 69 of the switch 59. When the control lever 62 is rocked leftwardly and rightwardly, the switch arm 69 is rocked respectively rightwardly and leftwardly to throw the switch into "on" and "off" positions, the switch 59, by reason of its toggle nature, snapping into its respective positions.

35 The above described structure and mechanism are common to record resurfacing machines heretofore manufactured and used, and form a part of the present invention only in so far as they are related to or combined with other mechanism hereinafter described.

40 To permit a setting of the resurfacing tool into operative position the machine must first be placed in a stopped condition. Thus an operation, in the use of a record resurfacing machine, which is normally associated with the operation of releasing the resurfacing tool from a set position is that of stopping the machine. The use of the machine may therefore be facilitated by the provision of means for automatically stopping the machine as an incident of releasing the tool from a set or operative position.

45 To automatically stop the machine when the resurfacing tool is released from a set position, either of the switches 51 and 59 heretofore described, or a suitable auxiliary switch, may be thrown to "off" position as an incident of such tool release. In the illustration of my invention an auxiliary switch, herein given the reference character 70, is shown for the above purpose. 50 This switch may be of the well known mercury type which is sensitive to angular position and may be also serially connected in the power circuit 54, as indicated in Fig. 5. With this arrangement, the power circuit 54 is opened, and 55 the machine is stopped, whenever any one of the switches 51, 59 and 70 is thrown to "off" position, and the power circuit is closed, and the machine is started, when all of the above mentioned switches are in their respective "on" positions.

70 The switch 70 comprises a glass bulb 71 containing a ball of mercury 72 and having a pair of terminals 73 extending outwardly therefrom; it is mounted on a bracket 74 and is held in place by a clamp 75 secured to the bracket by the

5 screws 76, a cushion 75' being inserted between the clamp 75 and the bulb 71. The bracket extends rearwardly of the carriage and is pivoted thereto by means of left and right forwardly extending legs 77 and 78 on the bracket which are hinged on a relatively long shoulder screw 79 provided on the right side of the carriage. The right leg 78 extends forwardly to form an arm 78' which is adapted to contact a cam 80 provided on the hub 42' of the lever 42. The bracket 74 is 10 biased downwardly, by its own weight, and the arm 78' is thereby biased upwardly into contact with the cam 80. By this contact of the arm 78' with the cam 80 the angular position of the mercury switch 70 is controlled, the cam 80 having such shape that when the tool-setting lever 42 is in its forward or set position the switch 70 is in a downwardly inclined position—the "on" 15 position of the switch—, as shown in Fig. 2, and when the lever 42 is in a rearward or released position the switch 70 is in an upwardly inclined position—the "off" position of the switch—, as indicated in dash-dot lines in Fig. 2.

20 When the resurfacing tool is set the switch 70 is prevented from being restored to its "on" position in order that the machine will not be started as an incident of tool setting. For this reason a latch 81 is provided for holding the switch 70 in its upwardly inclined, or "off", position. The latch 81 is pivoted by a screw 82 to a rearwardly 25 extending lug 83 on the carriage, is extended upwardly between the legs 77 and 78 of the bracket 74, and is biased towards the bracket 74, in a clockwise direction as it appears in Fig. 2, against a stop 84 by means of a tension spring 30 35.

tool is set while the main switch is yet in "on" position the auxiliary switch 70 is retained by the latch 81 in "off" position to prevent starting of the machine as an incident of such setting of the tool. After the tool is then set the auxiliary switch 70 may, however, be thrown to "on" position, to start the machine, by a simple manipulation of the control lever 62. The means for throwing the switch 70 by the control lever 62 comprises a rightwardly extending arm portion 90, provided on the plate 64, having an arcuately shaped cam slot 89. Connected to the arm portion 90 by a pin 88 engaging the cam slot 89 is a link member 87 which extends rearwardly along the rightward end portion of the machine below the base plate 1. The link member 87 is pivotally connected at its rearward end to an arm 91 of a lever 92 which is pivoted by a pivot screw 93 to a boss 93' extending downwardly from the base plate 1. The lever 92 has another arm 94 which is pivotally connected by a pin 95 to the right end of a laterally extending bar 96. The bar 96 is disposed in parallel relation to the longitudinal rod 21 and extends below and along the rear edge 25 of the opening 50 in the base plate. The bar is supported at its left end by a link 97 pivoted by a pivot screw 98 to a boss 98', such as the boss 93', and to the bar 96 by the pin 99. The bar 96 is thus mounted so that it may move forwardly and rearwardly in parallel motion.

On the right side of the carriage there is pivotally supported, by the shoulder screw 79, a lever 100 (best shown in Fig. 2) which is adapted to operatively connect the bar 96 with the latch 81, and as is hereinafter described, to also connect the bar 96 with the resurfacing tool-setting means. The lever 100 comprises a vertical lower portion 101 adapted to slidably contact the front edge of the bar 96; a central substantially semi-circular portion 102 pivoted at its upper end on the shoulder screw 79 adjacently of the right side of the carriage; and a bail portion 103 extending rightwardly beneath the screw 79 and terminating in a turned up lug 104 which is pivoted on the outer end portion of the screw 79 to secure a good bearing for the lever 100. The lever 100 is urged in a counter-clockwise direction to maintain its lower portion 101 in contact with the bar 96 by means of the spring 85 hereinbefore referred to, which spring is connected between a pin 102' on the lever 100 and the lower end 81" of the latch 81.

The link 87 is biased both forwardly and leftwardly by a tension spring 105 connected between the link and a pin 105' on the base plate, and the bar 96 is thus biased rearwardly, the most rearward position of the bar 96 being defined by the impingement of the bar against a stop lug 94' on the arm 94. When the switch 59 is in "on" position, the pin 88 carried by the link 87 is maintained, as by the leftward biasing of the link 87, in an inwardly extending notch 106 provided at the rearward end of the cam slot 89, as shown in Fig. 1. As the control lever 62 is rocked rightwardly toward its "off" position, the link 87 is moved rearwardly, the bar 96 is moved forwardly, and the lever 100 is thereby turned in a clockwise direction, as it appears in Fig. 2. As such turning of the lever 100 occurs a cross pin 107 on the lever contacts a cam face 108 on the rear edge of the latch 81 and thereby turns the latch in a counter-clockwise direction to free the notch 86 from the bracket 74. Such release of the latch 81 from the switch 70 causes the switch to return as by gravity to "on" position.

75 The means for releasing the latch 81 is ar-

ranged so that the release of the latch occurs before the control lever 62 reaches its mid or dead-center position. Since the main switch 59 is of the toggle variety it is not thrown unless the control lever 62 is moved through its dead-center position. Thus the latch 81 may be released to cause the auxiliary switch 70 to move into "on" position without throwing the main switch 59 to "off" position, such release of the latch being effected by merely moving the control lever 62 rightwardly through a minor portion of its travel as into an intermediate position which is before the dead-center position of the lever. Such intermediate position may in practice be readily defined by a lug 1', provided on the base plate 1 below the control lever 62, against which the operator may, for example, place his forefinger to form a stop for the control lever. Upon the release of the control lever 62 from such intermediate position, the lever snaps back into its leftward or "on" position by reason of the toggle nature of the switch 59.

When the control lever 62 is moved rightwardly to the intermediate position above mentioned the bar 96 is moved sufficiently ahead to cause the release of the latch 81 as heretofore described. Further rightward movement of the control lever 62 causes the bar 96 to be moved still further ahead. When the control lever 62 is moved rightwardly through the final portion of its travel to "off" position the pin 88 is released from the notch 106; the bar 96 is then moved rearwardly by the spring 105, but such rearward movement is restricted so as to retain the latch 81 in an inoperative position while the main switch 59 is in "off" position. To release the pin 88 from the notch 106 the link 87 is provided with a principally leftwardly extending front portion 87' having a cam face 109 on the end thereof. When the lever 62 enters into a final portion of its travel towards its "off" position the cam face 109 abuts against the boss 63 to limit the link 87 against leftward movement. The notch 89 moves, however, further leftwardly subsequent to the time the link 87 is so restricted in its movement, as by the movement of the control lever 62 towards "off" position, to cause the pin 88 to enter the cam slot 89. When this occurs the link 87 will move forwardly as because of the spring 105, the bar 96 then moving rearwardly. The spring 105 is, however, relatively light so that the link 87 is not moved substantially before the control lever 62 reaches its "off" position. When the control lever 62 is in "off" position the link 87 is restricted in its forward movement by the impingement of the pin 88 with the forward end of the cam slot 89. This causes the bar 96 to be held in an intermediate position while the switch is in "off" position, this intermediate position being such as to maintain the latch 81 in a fully inoperative position. Thus when the tool is set while the main switch 59 is in "off" position the auxiliary switch 70 returns, as by gravity, to "on" position. To start the machine subsequent to such setting of the tool the main switch 59 is thrown to "on" position.

An additional feature of my invention is to perform on the machine, as an incident of unlatching the end-gate 8 from its supporting position, various normally manually performed operations: 70 the throwing of the main switch 59 to "off" position to insure the stopping of the machine when the end-gate is opened, the releasing of the resurfacing tool from a set or operative position, and the ejecting of a record from the mandrel 18. 75

The throwing of the main switch 59 to "off" position by the unlatching of the end gate 8 may be first described.

Reference being had to Figs. 1 and 2, it will be seen that the end-gate latch 9 is secured to a shaft 110 which extends vertically through the right end portion 10 of the guide rail 11. The shaft 110 has upper and lower bearing collars 111 and 112, the upper bearing collar 111 fitting in a seat 113 to hold the shaft from downward movement. Secured by a pin 114 to the lower end of the shaft is a lever 115 having a forwardly extending arm 116 carrying a vertical pin 117 which loosely fits in a slot 118 provided in the arm portion 90 of the plate 64. When the switch 59 is in "on" position and the latch 9 is in operative position, as shown in Fig. 1, the pin 117 rests in the rearward end of the slot 118. Movement of the latch 9 to an inoperative position, as by turning the latch in a clockwise direction, will cause the pin 117 to impinge against the rearward edge of the slot 118 and to thereby turn the plate 64 in a counter-clockwise direction, thus throwing the switch 59 into "off" position. The return of the latch 9 to operative position while the switch 59 is in "off" position does not change the position of the switch, such return of the latch merely causing the pin 117 to traverse the length of the slot 118 and to come to rest in the forward position thereof as shown in Fig. 4.

The means for releasing the resurfacing tool from a set or operative position by the movement of the end-gate latch 9 to inoperative position may comprise principally the mechanism, heretofore described, for releasing the auxiliary switch 70 from its "off" position. It will be recalled that the moving of the control lever 62 through a minor portion of its travel towards "off" position causes the latch 81 to be released, or moved free from the bracket 74, to permit the switch 70 to move as by gravity to "on" position, and that the latch 81 is moreover held in a released or inoperative position while the switch 59 is in "off" position in order that the resetting of the tool, while the switch 59 is so positioned, will cause the switch 70 to return to "on" position. The throwing of the control lever 62 from "on" to "off" position causes, however, the lever 100 to be turned more than is necessary to release the latch 81. This movement of the lever 100, which is additional to that necessary to release the latch 81, is used to release the resurfacing tool from a set position. For this purpose the lever 100 is provided with an arm 119 extending forwardly from the lug 104 and terminating at a point below the arm 43 of the tool-setting lever 42, as shown in Fig. 2. When the control lever 62 is thrown from "on" to "off" position, which throwing may be effected by moving the end-gate latch 9 to inoperative position as heretofore described, the arm 119 contacts the arm 43 of the tool-setting lever 42 and moves the lever 42 in a clockwise direction, thereby causing the resurfacing tool to be released from a set or operative position.

The means for ejecting a record from the mandrel 18 by moving the end-gate latch 9 to inoperative position comprises a rearwardly extending arm 120 on the lever 115 to which is connected a vertical stud 121 projecting upwardly through an opening 122 in the base plate 1. Pivotedly connected to the stud 121, by a pivot screw 123, is a pawl 124 which lies above the base plate 1 and extends leftwardly to a position in front of the intermediate standard 5. The left end portion 124' of the pawl 124 is slidably supported

by a ridge 125 on the base plate, and is biased forwardly against a stop 126 by a tension spring 127 connected between the pawl and a pin 128 on the guide rail 11, the pawl having a cam face 129 which the stop 126 slidably contacts as is hereinafter described. The left end of the pawl has a beveled end face 130 and a hook 131 which is adapted to catch on a suitable pin 132 carried by a horizontal arm 133. The arm 133 is pivoted by a screw 134 to a boss 135 extending upwardly from the base plate, is biased leftwardly against a stop pin 136 on the base plate by a tension spring 137 connected between the arm and a pin 138 on the base plate, and is pivoted at its rearward end, by a pin 139, to a rod 140 which extends slidably, in a lateral direction, through the intermediate standard 5. The rod 140 carries at its rightward end a shoe 141 adapted to abut against the adjacent end of a record mounted on the mandrel 18. The operation of the above-described record ejecting means is as follows:

When the end-gate latch 9 is moved to inoperative position the pawl 124 is moved in a rightward direction. Such movement of the pawl cause the arm 133 to be also moved rightwardly as by the engagement of the hook 131 with the pin 132. The rightward movement of the arm 133 causes the shoe 141 to abut against the left end wall of the record 19 and to thereby eject the record from the mandrel 18. A rightward movement of the pawl 124 causes its left end portion 124' to be moved rearwardly, as by the contact of the pin 126 with the cam face 129, so that the hook 131 will be rendered free from the pin 132 at the time the record ejection is completed. Such freeing of the hook 131 from the pin 132 causes the arm 133 to snap leftwardly, as by the spring 137, thereby restoring the shoe 141 to its unoperated position shown in Fig. 1. The freeing of the hook 131 from the pin 132 also removes the biasing force from the pawl 124, as caused by the spring 137. The end-gate latch 9 is then no longer urged into operative position. As the end-gate latch 9 is, however, returned to operative position the bevelled end face 130 of the pawl 124 slides over the pin 132 and the hook 131 again engages the pin to restore the record ejecting means for reoperation, the end-gate latch 9 being then resiliently held in operative position by the spring 137.

Although I have shown and described a single embodiment of my invention, it will be understood that many modifications and changes may be made therein without departing from the scope of my invention, which I undertake to express according to the following claims.

I claim:

1. In a phonograph record resurfacing machine having a record-supporting mandrel: the combination of an end-gate for said mandrel movable into and out of a mandrel-supporting position; latching means for releasably holding said end-gate in said mandrel-supporting position; means for controlling the operation of the machine; and means, operated by said latching means, for operating said control means.

2. In a phonograph record resurfacing machine having a record-supporting mandrel: the combination of an end-gate for said mandrel; a latch for said end-gate having latching and unlatching positions; an "off" and "on" switch means operable to control the machine; and means, operated by said latch as the latter is moved from latching to unlatching positions, for operating said switch means from "on" to "off" positions.

3. In a phonograph record resurfacing machine having a record-supporting mandrel: the combination of an end-gate for said mandrel; a resurfacing tool movable between operative and inoperative positions relative to a supported record; a latch for said end-gate; and means, controlled by said latch, for moving said tool between said operative and inoperative positions. 5
4. In a phonograph record resurfacing machine having a record-supporting mandrel: the combination of an end-gate for said mandrel movable into a mandrel-supporting position; latching means for releasably holding said end-gate in said mandrel-supporting position; a resurfacing tool movable into an operative position relative to a supported record; and means operated by said latching means incidental to the release of said end-gate from mandrel-supporting position for causing the return of said resurfacing tool from said set position. 10
5. In a phonograph record resurfacing machine having a record-supporting mandrel: the combination of an end-gate for said mandrel; latching means for said end-gate; means for ejecting a record from said mandrel; and means, controlled by said latching means, for operating said record-ejecting means. 15
6. In a phonograph record resurfacing machine having a record-supporting mandrel: the combination of an end-gate for said mandrel movable into a supporting position; latching means for holding said end-gate in said supporting position; record-ejecting means; and means, operatively connecting said latching means with said record-ejecting means, for causing the operation of said ejecting means upon the release of said end-gate from said supporting position. 20
7. In a phonograph record resurfacing machine having a record-supporting mandrel: the combination of an end-gate for said mandrel having supporting and non-supporting positions; means biasing said end-gate into non-supporting position; latching means for holding said end-gate in supporting position; record-ejecting means; and manipulatable means for operating said record-ejecting means and for coordinately releasing said latching means to permit said biasing means to move said end-gate into non-supporting position. 25
8. In a phonograph record resurfacing machine having a record-supporting mandrel: the combination of an end-gate for said mandrel adapted to be held in a supporting position during the operation of the machine, and movable therefrom into a non-supporting position; record-ejecting means; and means operable by a single manipulation thereof to cause said record-ejecting means to be rendered operative and to coordinately cause said end-gate to be moved into non-supporting position. 30
9. In a phonograph record resurfacing machine having a record-supporting mandrel: the combination of an end-gate for said mandrel; a latch for said end-gate movable into inoperative position; a record ejector biased into unoperated position; and means for automatically operating said record ejector incidental to the movement of said latch to inoperative position, said means being adapted to permit return of said record ejector to normal or inoperative position after said latch is moved a predetermined extent. 35
10. In a phonograph record resurfacing machine having a support for a record: the combination of a resurfacing tool movable into and out of operative position relative to a supported record; switch means for controlling the operation of the machine; and means, controlled by said tool, for controlling said switch means. 5
11. In a phonograph record resurfacing machine having a support for a record: the combination of a resurfacing tool movable into and out of operative position relative to a supported record; means for controlling the operation of the machine; and means, operatively connecting said resurfacing tool with said controlling means, for causing operation of the latter as an incident of moving the former. 10
12. In a phonograph record resurfacing machine having a support for a record: the combination of a resurfacing tool settable into operative position relative to a supported record; switch means having "off" and "on" positions, for controlling the operation of the machine; and means operated incidental to the return of the set tool to inoperative position for causing said switch means to be moved from "on" to "off" 15 position. 20
13. In a phonograph record resurfacing machine having a support for a record: the combination of a resurfacing tool settable into an operative position relative to a supported record; an openable and closeable power circuit for the machine; and means, controlled by said resurfacing tool, for opening said power circuit as the set tool is returned to inoperative position. 30
14. In a phonograph record resurfacing machine having a support for a record: the combination of a resurfacing tool having operative and inoperative positions relative to a supported record; a power circuit; a main control switch and an auxiliary control switch serially connected in said power circuit and each having "off" and "on" positions; means for throwing said auxiliary switch to "off" position as said tool is moved to inoperative position; means for holding said auxiliary switch in "off" position when said tool is subsequently moved to operative position; and means operatively connected with said main switch for controlling the release of said switch-holding means. 35
15. In a phonograph record resurfacing machine: the combination of a resurfacing tool movable into operative and inoperative positions relative to a record to be resurfaced; main and auxiliary control switches each having "off" and "on" positions; means for throwing said auxiliary switch to "off" position as said tool is moved to inoperative position; latching means for holding said auxiliary switch in "off" position; manipulatable means for controlling said main switch; and means controlled by said manipulatable means for releasing said latching means. 50
16. In a phonograph record resurfacing machine: the combination of a resurfacing tool movable into operative and inoperative positions relative to a record to be resurfaced; a control switch having "off" and "on" positions and biased into one of said positions; means for throwing said control switch into the other of said positions as said tool is moved into inoperative position; and a manually controlled latch for releasably holding said control switch in said other position. 65

CHARLES HUENLICH.
